UNITED STATES PATENT OFFICE.

EDWARD McGOWAN, OF MULBERRY, KANSAS.

MINING-MACHINE.

1,077,418.

Specification of Letters Patent.

Patented Nov. 4, 1913.

Application filed June 14, 1912. Serial No. 703,683.

To all whom it may concern:

Be it known that I, EDWARD McGOWAN, a citizen of the United States, and a resident of Mulberry, in the county of Crawford and State of Kansas, have invented a certain new and useful Improvement in Mining-Machines, of which the following is a specification.

My invention relates to improvements in mining machines.

It is particularly adapted to mining machines of the type which is provided with an endless traveling belt to which a radial movement is imparted and which has laterally extending cutters adapted to cut a kerf in the wall of a mine chamber or tunnel. With this type of machine it is ordinarily necessary to employ anchoring means for holding the machine as a whole stationary, or to employ devices, such as windlasses and ropes for forcing the machine toward the work.

One object of my invention is to provide a mining machine which will dispense with anchoring devices, windlasses and such devices, and which may be easily and quickly operated by one attendant, and readily moved into the various positions required to effect the work desired to be done.

My invention provides further a mechanism which may be readily operated without interfering with or being interfered by the props usually employed in mine chambers.

I have found that in the use of an endless belt having laterally extending cutters, if suitable supporting means is provided, the cutting mechanism itself may be employed to draw the machine bodily toward the work.

My invention, therefore, provides such a supporting mechanism. I have also found that by providing the supporting means with a suitable guard, this guard traveling along and bearing against the wall of the mine in which the kerf is being cut, will hold the machine back so that the cutting mechanism can not choke down.

My invention provides further novel means for effecting the proper disposition of the means for supporting the cutting mechanism, whereby the cutting mechanism may be applied at the proper angle relative to the horizontal and have the required radial movement imparted to it.

Other novel features of my invention are hereinafter fully described and claimed.

In the accompanying drawings, which illustrate the preferred form of my invention, as applied to a radially movable endless belt cutting mechanism, Figure 1 is a side elevation of the machine, the cover being shown in vertical section. Fig. 2 is a plan view of the machine, the cover being shown in horizontal section. Fig. 3 is a vertical section on the line *a—b* of Fig. 2. Fig. 4 is a vertical section, enlarged on the line *c—d* of Fig. 2. Fig. 5 is a plan view partly broken away of a portion of the forward part of the machine. Figs. 6 and 7 are diagrammatic views showing different operative positions of the machine in a mine chamber.

Similar reference characters designate similar parts in the different views.

1 designates the body of a truck having wheels 2 adapted to run upon the rails 3 of a track which leads toward the wall 4 in which it is designed to cut a kerf 5, Figs. 6 and 7, at a level substantially in the plane of the floor of the chamber or tunnel.

Pivoted by a horizontal bolt 6 to the forward portion of the body 1 of the truck is an upwardly and downwardly swinging frame 7, which is supported in and moved to the desired positions by blocks or nuts 8 respectively resting upon wedges, 9 supported by the body 1. The blocks or nuts 8 are respectively mounted on horizontal longitudinal rotary screws 10, the rear ends of which are respectively rotatively supported in brackets 11 secured to the frame 7, the other ends of said screws being rotatively mounted in bearings 12 respectively, which bearings are also secured to the frame 7.

Rigidly secured respectively to the screws 10 forward of and adapted to bear against the brackets 11 are bevel pinions 13 which respectively mesh with bevel pinions 14 secured to and rotative with a horizontal transverse shaft 15 rotatively mounted in the brackets 11. Opposite ends of the shaft 15 are preferably squared, as shown, so as to be readily gripped with a crank or wrench, not shown, by which the shaft is turned so as to effect an adjustment of the swinging frame 7 by the mechanism just described. Fixed on the forward ends of the screws 10 and adapted to bear against the forward sides of the bearings 12 respectively are collars 16. By turning the shaft 15 in the proper direction the blocks or nuts

8 may be drawn rearwardly on the wedges 9, thereby elevating the rear end of the frame 7. By turning the shaft 15 in the opposite direction, the blocks or nuts 8 will be moved forwardly on the wedges 9, and the frame 7 will then lower by gravity.

Supporting means comprising a horizontal platform 17 is radially mounted on the frame 7 to which it is pivoted by a bolt 18 which is disposed vertically when the frame 7 is disposed in the horizontal position shown in Fig. 1 and Fig. 3. The said supporting means is also provided with a forwardly extending arm 19, of any desired form and construction, and which has its rear portion firmly secured to the platform 17. This arm 19 carries adjacent to its forward end a substantially horizontally disposed sprocket wheel 20 rotatively mounted, 20 and having suitable means for being adjusted forward and backwardly on the arm 19 for the purpose of tightening or loosening an endless chain belt 21 mounted on the sprocket wheel 20 and on a sprocket wheel 22 which is secured to and rotative with a vertical shaft 23 rotatively mounted in bearings 24 and 25, secured respectively to the upper side of the platform 17, and to the underside of the arm 19, as shown in Fig. 3. 30 The belt 21 is provided with cutters 26 which extend laterally beyond the belt and are adapted to cut the kerfs 5.

Any suitable means may be provided for driving the chain belt 21. In the drawings I have shown rigidly affixed to the shaft 23 a spur gear wheel 27 which meshes with a pinion 28 rotatively mounted on a vertical stud 29 the lower end of which is secured to the bearing 24. Also rotative on the stud 40 29 and secured to the pinion 28 is a bevel gear wheel 30 which meshes with a bevel pinion 31 secured to and rotatable with the armature shaft 32 of an electric motor 33, which is supported on the platform 17 over the truck frame 7 and to the rear of the pivot bolt or king pin 18, the weight of the motor being thus employed to balance the weight of the forward part of the platform, its arm and the cutting mechanism. A suitable cover or housing 34 may be mounted removably on the platform 17 to protect the motor and adjacent gearing. The under side of the platform 17 may be provided with casters 35 which rest upon the frame 7. 55 Any suitable means may be employed to give the platform 17 a swinging or radial movement about the bolt 18 as an axis. In the drawings I have shown for this purpose an arcuate rack 36 which is rigidly secured to the frame 7 and has at its center the bolt 18. Meshing with the rack 36 is a pinion 37 which is rigidly secured to a vertical shaft 38 extending through and rotatively mounted in the platform 17. Secured to 60 said shaft 38 is a worm wheel 39 which is

engaged by a worm shaft 40 disposed horizontally above the platform and rotatively mounted in bearings 41 secured to said platform 17. Secured to the rear end of the shaft 40 is a hand wheel 42 by which the shaft may be turned. By turning said shaft the platform 17 together with the arm 19 may be radially swung through the intermediacy of the worm wheel 39, shaft 38, pinion 37 and rack 36.

The forward end of the platform 17 is preferably arcuate to afford a bearing surface adapted to travel along and bear against the wall 4 when the kerf is being cut. The center of the circle of the arcuate bearing surface 43 is, preferably, the axis of the platform 17 or the bolt 18.

In starting a cut through a plane wall at one end or side of the mine chamber, the machine is disposed, first, as shown in Fig. 6, with the belt 21 disposed longitudinally in the middle of the track, as shown in solid lines in Fig. 6. The motor 33 is then started, thereby driving the belt. With the cutters 26 disposed, as shown in the drawings, the motor is run so as to drive the belt 21 clockwise, the forward end of the belt being forced against the wall to start the kerf. As the cutters 26 cut away the material, the hand wheel 42 is turned so as to swing the arm 19 and belt 21 to the angular position shown in dotted lines in Fig. 6, by means of the mechanism hereinbefore described. The hand wheel 42 is then operated so as to cause the platform 17 and belt 21 to be swung clockwise as indicated by the dotted arrow in Fig. 6. An extension of the track is then made, after the material above the kerf thus cut has been removed, and the platform 17 is again swung to the angular position shown in solid lines in Fig. 7. The machine is now moved bodily forwardly on the track, the belt 21 being held in the angular position last described until the belt 21 reaches the position shown in dotted lines in Fig. 7. The platform 17 and belt 21 are then swung clockwise by operating the hand wheel 42, so that the cutters cut out a kerf 5. The belt 21 and platform 17 may then be withdrawn to permit the removal of the material above the kerf thus cut, after which another section of track may be laid and the machine adjusted to the position corresponding to the one shown in solid lines in Fig. 7, after which the machine is again moved bodily forward and then the belt 21 and platform 17 are swung clockwise to cut another kerf. In like manner, the machine is operated in successive steps.

In Figs. 6 and 7 are shown the usual props 44. It will be seen that as my machine does not have to be anchored to hold it stationary, but is readily moved forwardly as the cutting is being effected, the machine may be used so as to easily avoid the props. As the

belt 21 with its cutters 26 in running tends to draw the machine toward the work, and as the machine is mounted on a track along which it can run toward the wall in which the kerf is being cut, there would be a liability of the belt being choked by its pulling action which operates to cause it to further enter the wall. By providing the arcuate guard 43, the machine is held back when this 5 guard strikes the wall, thus preventing the choking of the belt. By having this guard of an arcuate form on its bearing surface, and the center of the arc being the bolt 18, the axis of the platform 17, the guard 43 will 10 travel along and bear against the wall as the belt 21 is swung radially in making the cut, without offering such friction to the turning of the platform 17 as would be annoying or as would affect the radial movement of 15 the platform.

I do not limit my invention to the structure shown and described, as modifications of my invention, within the scope of the appended claims, may be made without departing from the spirit of my invention.

Having thus described my invention, what I claim and desire to secure by Letters Patent, is:—

1. In a mining machine, carrying means 30 adapted to be freely moved forward during the operation of the machine, cutting means adapted to cut a kerf in the wall of a mine, and supporting means pivoted to the carrying means and carrying 35 the cutting means and having a guard

adapted to travel along and bear against the wall of a mine, the bearing surface of said guard being an arc the center of which is the axis on which the supporting means swings.

2. In a mining machine, a track, a wheeled truck adapted to run on said track, and to be moved freely forward during the cutting operation, cutting means adapted to cut a kerf in a wall of a mine, and supporting 45 means carrying the cutting means and pivotally mounted on the truck and having a guard adapted to travel along and bear against the wall during the cutting operation, the guard having an arcuate bearing surface the center of which is the axis of 50 said supporting means.

3. In a mining machine, pivotally mounted supporting means having an arcuate guard adapted to travel along and bear 55 against the wall of a mine during the cutting operation, the bearing surface of the guard being an arc the center of which is the axis of the supporting means, and cutting means carried by the supporting means and 60 in operation being adapted to force the guard toward the work and against the wall.

In testimony whereof I have signed my name to this specification in the presence of two subscribing witnesses.

EDWARD McGOWAN.
